TOY CONSTRUCTION PIECE

Raymond F. Stockton, 500 West Ave. K,
Lancaster, Calif.

Filed Apr. 16, 1965, Ser. No. 84,837

Term of patent 7 years

(Cl. D34—15)

FIG. 1 is a perspective view of a toy construction piece, showing my new design,

FIG. 2 is a top plan view having reference to the position shown in FIG. 1,

FIG. 3 is a side elevational view of the side opposite that shown in FIG. 1,

FIG. 4 is a bottom plan view having reference to FIGS. 1 and 3,

FIG. 5 is an end elevational view,

FIG. 6 is a transverse sectional view taken on the lines 6-6 of FIG. 3, and

FIG. 7 is a transverse sectional view taken on the lines 7-7 of FIG. 3.

I claim:

The ornamental design for a toy construction piece, substantially as shown.
